SPONGE MOP HEAD OR SIMILAR ARTICLE

Elmer Cornell, Stamford, Conn., and John F. Imhof,
Port Chester, N.Y., assignors to Empire Brushes, Inc.,
Port Chester, N.Y., a corporation of New York

Filed Mar. 12, 1964, Ser. No. 78,969

Term of patent 14 years

(Cl. D9—2)

FIG. 1

FIG. 1 is a top plan view of a sponge mop head embodying the new design;

FIG. 2 is a side elevational view thereof;

FIG. 3 is a cross-sectional view taken on line 3—3 of FIG. 2;

FIG. 4 is a cross-sectional view taken on line 4—4 of FIG. 1;

FIG. 5 is a cross-sectional view taken on line 5—5 of FIG. 1; and

FIG. 6 is a cross-sectional view taken on line 6—6 of FIG. 1.

We claim:
The ornamental design of a sponge mop head or similar article, substantially as shown.
